UNITED STATES PATENT OFFICE.

CORNELIUS BEARD, OF NEW YORK, N. Y.

LOCOMOTIVE-BRAKE.

SPECIFICATION forming part of Letters Patent No. 309,122, dated December 9, 1883.

Application filed November 10, 1883. (No model.)

To all whom it may concern:

Be it known that I, CORNELIUS BEARD, a citizen of the United States of America, residing at New York, in the county of New York 5 and State of New York, have invented certain new and useful Improvements in Locomotive-Brakes, of which the following is a specification, reference being had therein to the accompanying drawings.

10 This invention relates to an improvement in locomotive-brakes; and it consists in the peculiar combinations and the construction and arrangement of parts hereinafter more fully described, and then pointed out in the claims, 15 whereby an equal pressure is exerted on each shoe, and the pressure on the journals and boxes equalized without requiring the use of fixed fulcrums between the equalizers and brake-shoe, thus avoiding the loss of power 20 due to the use of said fixed fulcrums and the connections between the equalizers and levers heretofore employed.

In the accompanying drawings, Figure 1 represents a reversed plan view of a portion 25 of the frame and wheels of a locomotive, and Fig. 2 an elevation of the same.

A represents the frame, to which is pivoted the hangers B, carrying the brake-heads C. To these brake-heads are attached in any convenient manner the equalizers E, E', E'', E³, 30 E⁵, and E⁶. All the equalizers on each side are connected together by rods F, F', F'', F³, and F⁴, of which the long ones may have a turn-buckle, by means of which they may be 35 adjusted in length, as desired, to take up the slack and prevent lost motion from wear in the shoes or other parts, or to adjust the position of the parts to act to the best advantage. The forward equalizer of each side is connected to the frame by a rod, F⁵, and eyebolt G; but any other style of connection may be 40 used, if preferred. The rear equalizers are connected by rods F⁶ to levers H, the short end of which may be connected with the tender 45 by the rods F⁷, or may be pivoted to some part of the frame. The long ends of the levers are connected by links I to an equalizer, J, to the center of which is connected in any convenient manner the rod F⁸, which in turn is 50 connected with any brake-operating device—such as a drum and chain operated by a fric-

tion-wheel running in contact with one of the axles of the tender—or motion may be given to the brakes by any convenient means, many of which are well known to mechanics, and 55 are therefore unnecessary to describe here.

The operation is as follows: Motion being given to the rod F⁸, it operates through the equalizer J and links I upon the levers H H, which, being fulcrumed on the rods F⁷, pull on 60 the equalizer E, which brings the brakes directly connected to them into action, and at the same time pull on the equalizers E', which in turn act through the rods F' upon the equalizers E'', and so on through the different 65 rods until all the equalizers are brought into action and press the brakes equally upon all the wheels.

It will be observed that the hangers are the only parts of the brake connected to the frame 70 of the engine, with the exception of the forward equalizer, and this, as well as the hangers, may be connected to the frame by clevises to obviate the necessity of boring holes in the frame in cases where this would be objectionable. 75 From this it will be seen that this system of brakes can be readily attached to locomotives now in use without making any essential change in them, or the necessity of taking them to the shops. Besides this, my apparatus has the advantages of being of few parts 80 and very simple, and is therefore cheap, very durable, and not likely to get out of order, adapted to give an equal pressure on each side of each wheel, and thus unequal strains and 85 wearing of journals are obviated; and, what is still more important, I can get a great brake-pressure from a comparatively limited amount of power, which is due to the fact that I do not lose any of the brake power by expending it 90 on fixed bearings, as all the force developed is exerted upon the brakes.

It is evident that, in lieu of the rods F F', &c., chains may be substituted; but I prefer the rods.

In some cases I may use the levers H H in lieu of the equalizers E, in which case the short ends of the levers will of course be attached to the brake-heads; but I prefer the arrangement shown. The levers in this case 100 will become the equivalents of the equalizers E.

I have shown three pairs of locomotive-

wheels in my drawings; but it is evident that my invention may be used in connection with a greater or less number of wheels, and that its use is not confined to locomotives.

5 It will be observed that by my arrangement of the equalizers, acting directly on the brake-heads, I combine the advantages of having equal pressure on both sides of the wheels with that of the absence of loss of power due to fixed fulcrums. So far as I am aware I am the first to combine these advantages.

I am aware that brakes having equalizers hung upon movable fulcrums, but arranged to press unequally upon the wheels, have been used; and I am aware that horizontal equalizers arranged between the wheels have been used; but in such cases the connections between the equalizers were arranged in a manner essentially different from mine, and the 20 ends of the equalizers were not connected directly to the brake-heads, but were pivoted to brake-levers having fixed fulcrums, which my invention is essentially designed to avoid; and I am also aware that shoes have been 25 pivoted directly to equalizers; but in such arrangements the blocks were pivoted to the center of the equalizers, which necessitated that their ends should project beyond and outside of the wheels, thus requiring heavy plates 30 to be attached to the car to protect them from damage.

What I claim as new is—

1. The combination, with a series of brakes, of a series of pairs of equalizers, each pair 35 hung between two wheels, each equalizer having its outer end connected direct to a brake-shoe, each connected at its inner end to the equalizer acting on the next adjacent wheel, and each connected at a point between its end 40 to an equalizer acting on the other side of its own wheel, substantially as described.

2. The combination, in a brake apparatus, of a series of wheels, each wheel having a pair of brake-heads hung one on each side, each head having the outer end of an equalizer connected 45 directly to it, the two equalizers bearing on the brake-heads of each wheel being connected together at a distance from their ends, and one lever of each pair being connected to the lever of the next pair, whereby an equal pressure is 50 exerted on each shoe, substantially as described.

3. The combination, in a brake apparatus, of a pair of hangers, B B, the two hangers being suspended on the opposite sides of a wheel, a 55 pair of brake-heads, C, supported by said hangers, a pair of equalizers, E E', each having its end connected directly to a brake-head, and the rod F, connecting the two equalizers, arranged on the inner side of the wheel, all 60 constructed, arranged, and operating substantially as shown and described.

4. The combination, in a brake apparatus, of a series of pairs of hangers, B B, each pair arranged on the opposite sides of a wheel, a corresponding series of brake-heads, C C, supported by said hangers, and a corresponding series of pairs of equalizers, each equalizer having its outer end connected directly to a 65 brake-head, and each pair having a rod connecting them at a distance from their ends, and one equalizer of each pair connected to the nearest equalizer of the next pair by a rod 70 pivoted to their inner ends, substantially as described.

In testimony whereof I affix my signature, in presence of two witnesses, this 25th day of October, 1883.

CORNELIUS BEARD.
